UNITED STATES PATENT OFFICE

2,436,119

MATTRESS FILLING BOX

Frederick Parker, Houston, Tex.

Application September 24, 1942, Serial No. 459,600

2 Claims. (Cl. 45—138)

1

This invention relates to a mattress filling box. An object of the invention is to provide a mattress filling box specially adapted for use in the manufacture of mattresses containing a fibrous filler.

Another object of the invention is to provide a mattress filling box designed to contain the mattress covering, or tick, to be filled and which is of such construction as to readily permit the passage of air there through and which is of such shape as to restrict the ends of the tick vertically and to allow the vertical expansion of the intermediate portion of the tick and thus produce a uniform crowned center, which mattress in use will pack uniformly from end to end.

More specifically an object of the invention is to provide a mattress filling box formed of upper and lower frames whose facing sides are arcuate from end to end and are formed of screening, such as wire mesh, so as to not obstruct the passage of air, the upper frame being hinged at one end and releasably secured, at its other end, in a fixed relation to the lower frame while the tick, or covering, is being filled with the cotton or other fibrous material; said frames being so shaped, as above described, to the end that the end zones of the covering will be restricted more than the intermediate zone so that when the cover is filled with fibrous material the mattress will have a uniform crowned center.

Another object of the invention is to provide a mattress filling box that may be readily opened for the insertion of the cover or for the removal of the mattress after it has been filled.

With the above and other objects in view the invention has particular relation to certain novel features of construction, arrangement of parts and use, an example of which is given in this specification and illustrated in the accompanying drawings herein:

Figure 1 shows a side elevation, partly in section.

Figure 2 shows a plan view and

Figure 3 shows a cross-sectional view taken on the line 3—3 of Figure 1.

Referring now more particularly to the drawings wherein like numerals of reference designate the same parts in each of the figures the numerals 1 and 2 designate, respectively, upper and lower skeleton frameworks which may be composed of any suitable material such as wood or metal.

The lower framework may be permanently located on a suitable support such as the floor 3.

2

The upper framework is spaced above the lower framework and at its rear end is hinged to a suitable upright, such as the wall 4, by the hinges 5, 5.

5 A cable 6 is attached at one end, to the forward end of the framework 1, and this cable works over the overhead sheaves 7, 7 suspended from the overhead ceiling. The other end of the cable 6 carries a counterweight 8. The upper framework is thereby counterbalanced and may be easily lifted and lowered.

10 The facing sides of the upper and lower framework are concaved or curved, from end to end as shown and said facing sides are composed of foraminated material such as wire mesh 9, 10.

15 The mattress covering, or tick, 11, formed of fabric is placed between the upper and lower frames preparatory to filling it with lint cotton or other fibrous material.

20 This fibrous material is conditioned by a suitable machine as 12 and delivered, under air pressure, through the wide chute 13 into the covering 11. For this purpose the forward end of the covering is open and is clamped around the adjacent end of the chute 13 by means of a clamp 14.

25 While the tick is being filled the upper frame is held down by means of a releasable hook 15 which is connected, at one end, to the chute and whose other end engages through an eye 16 on the forward end of the upper frame.

30 The air entering the tick, or covering, 11 will inflate the latter and said air will pass on out through the fabric covering and out through the wire mesh 9, 10 with a minimum of obstruction.

35 The lint cotton or other fiber will be carried along in the air current and will be deposited first in the end of the tick, or covering, remote from the chute and said covering will be gradually filled from end to end. The ends of the mattress covering are contracted by the ends of the upper and lower frames, as shown in Figure 1, so that less fiber will be deposited in the ends than along the intermediate portions so that the mattress

40 will be uniformly crowned on its upper and under sides and from end to end so that when the mattress is subjected to use its intermediate portion which sustains the main weight of the body of the sleeper will contain more of the filling material than the ends which are subjected to minor portions of the weight. Accordingly the mattress will in use eventually assume a substantial uniform vertical thickness from end to end.

45 When the covering 11 has been completely filled 50 the hook 15 may be disengaged and the forward

end of the framework 1 easily lifted. The clamp 14 may be then released and the covering 11 disengaged from the chute 13 and closed and the mattress then removed from the filling box.

The drawings and description are illustrative merely while the broad principle of the invention will be defined by the appended claims.

What I claim is:

1. In combination, an upper frame, a lower frame coinciding with and spaced from the upper frame means for pivoting one of said frames, at one end, so that the pivoted frame may move relative to the other frame, the facing sides of the frames being concave from end to end and said frames being formed with open work covered with foraminated material throughout, a fabric sack between the frames and of substantially the same length and width as the frames and a chute of substantially the same width as the frames and sack and entering one end of the sack said sack being formed of open work material to allow the air to pass therethrough.

2. In combination, an upper frame, a lower frame coinciding with and spaced from the upper frame, means for pivoting one of said frames, at one end, so that the pivoted frame may move toward and from the other frame, the facing

sides of the frames being concaved from end to end, foraminated material covering the facing sides of said frames, a fabric sack between the frames and of substantially the same length and width as the frames and formed of material that will allow the air to pass therethrough, an inlet chute of substantially the same width as the sack and entering one end of the sack and means for delivering a lint-like filler through said chute 10 and into said sack to fill the sack.

FREDERICK PARKER.
